Chas. L. Byron

Inventor:
Harry S. Hart,

By Wilkinson & Shulley
Atty.

UNITED STATES PATENT OFFICE.

HARRY S. HART, OF CHICAGO, ILLINOIS, ASSIGNOR TO NATIONAL DUMP CAR COMPANY, OF CHICAGO, ILLINOIS, A CORPORATION OF MAINE.

RAILWAY-CAR-DOOR ARRANGEMENT.

Application filed October 23, 1919. Serial No. 332,638.

To all whom it may concern:

Be it known that I, HARRY S. HART, a citizen of the United States, residing at Chicago, in the county of Cook and State of Illinois, have invented certain new and useful Improvements in Railway-Car-Door Arrangements, of which the following is a specification.

This invention relates to railway cars, and 10 more particularly to door arrangements therefor.

Car doors such as the dump doors for general service cars have to be taken off and put on relatively frequently as a result of 15 necessary repairs. Heretofore these dump doors have been hinged in rather a permanent manner so that considerable time and effort are required to put on and take off such doors.

Accordingly, one object of my invention 20 is to provide a simple and efficient arrangement whereby dump doors may be put on and taken off with great rapidity and ease.

Another object is to provide a simple de- 25 mountable hinge arrangement for dump doors.

These and other objects are accomplished by means of the arrangement disclosed on the accompanying sheet of drawings, in 30 which Figure 1 is a transverse sectional view of a general service car embodying my invention; and Figure 2 is a detail view of the hinge construction of the door.

This general service car includes sides 10, 35 ends 11 and a floor composed largely of doors 12, which are hinged at their inner edges to the center sill structure 13. The car includes transverse frame members 14 provided with slots 15, in which shafts 16 are 40 laterally movable. These shafts when located at the inner ends of the slots and underlying the doors 12 act as supports for the latter.

It will be understood that when the shafts 45 are moved outwardly to the outer limits of the slots 15, the doors are free to drop into an open position. The doors 12 are supported in open position by suitable stop members 17 supported by the cross frame members 14.

This invention has to do primarily with 50 the doors 12 and more particularly with the mounting therefor. These dump doors 12 are relatively heavy and accordingly rather difficult to handle. Mounting these relatively heavy dump doors on hinges in the

old manner takes considerable time and effort and, as pointed out hereinabove, it is advantageous to be able to rapidly mount and dismount such dump doors with respect to their hangings. 60

I have provided a readily demountable arrangement in which pivot pins or members 18 are provided and as here shown are associated with the center sill structure 13. Each of the doors is provided with a plurality of hinge members 19 which are in the form of open hooks 20, which hook over and pivot around the pivot members 18. The hook portion 20 of the hinge member extends through a large enough arc to prevent 70 the door from becoming accidentally disengaged from its mounting, but at the same time is just embracive enough in its action with respect to the pivot pins 18 to make it possible readily to disengage the hinge 75 member 19 for mounting and demounting the door.

It will be understood, of course, that the door cannot be demounted when in its closed or horizontal position, as shown at the left 80 hand side of the figure. This door is mounted and demounted when in open position, as shown at the right hand side of the figure. To mount and demount the door, it is merely necessary to pivot the same about the stop 85 member 17, as shown at the right hand side of the figure, whereby the open hooked portion 20 may be elevated above the pivot member 18 and then either forced over the pin to secure the door in place or withdrawn 90 from the pivot member 18 for demounting the door. The mounting and demounting action may be done with great rapidity and ease.

It will be noted that the door is mounted 95 by applying the hook over the pivot member and then permitting the hook to lower, said door being demounted by raising the hook from the pivot member and then moving the door outward away from the center sill. 100 It will also be noted that the doors may be mounted and demounted without disturbing the position of the pivot pin. Attention also is called to the fact that the doors are wholly free from the door operating 105 mechanism or shafts, there being no chain or other connection between the doors and shafts. This combination, therefore, presents an arrangement whereby the doors may be mounted and demounted in a simple and 110

efficient manner and in a minimum amount of time, and at the same time independent of any interference with the door operating mechanism.

5 It is my intention to cover all modifications of the invention falling within the spirit and scope of the following claims.

I claim:

1. In a general service car, a rigid car member, a fixed pivot member located adjacent thereto, a door, said door having a hinge member adapted to be removably associated with the pivot member, the clearances between the several members being such that the hinge may be removed from the pivot only when the door is in the open position.

2. In a general service car, a rigid car member, a fixed pivot member located adjacent thereto, a door, said door having a

hinge member adapted to be removably associated with the pivot member, the clearances between the door and rigid car member being such that the hinge may be removed from the pivot only when the door is in the open position.

3. In a general service car, a rigid car member, a fixed pivot member located adjacent thereto, a door, said door having a hinge member in the form of an open book for embracing a portion of said pivot member and being removable therefrom when the door is open, the clearances between the door and rigid car member being such as to prevent such removal when the door is closed.

Signed at Chicago, Illinois, this 16th day of October, 1919.

HARRY S. HART.
